No. 845,546.

PATENTED FEB. 26, 1907.

A. E. HARRISON & C. M. HASLETT.

TELEPHONE MAGNET.

APPLICATION FILED SEPT. 8, 1905.

UNITED STATES PATENT OFFICE.

AARON E. HARRISON, OF NEW YORK, N. Y., AND CROWELL M. HASLETT, OF JERSEY CITY, NEW JERSEY.

TELEPHONE-MAGNET.

No. 845,546.

Specification of Letters Patent.

Patented Feb. 26, 1907.

Application filed September 9, 1905. Serial No. 277,668.

To all whom it may concern.

Be it known that we, AARON E. HARRISON, a resident of the city of New York, borough of Manhattan, in the county and State of New York, and CROWELL M. HASLETT, a resident of Jersey City, in the county of Hudson and State of New Jersey, both citizens of the United States, have invented a new and Improved Telephone-Magnet, of which the following is a full, clear, and exact description.

Our invention relates to magnets, and more particularly to telephone-magnets in which it is desirable to increase to a maximum the number of lines of magnetic flux confined within a given area.

To this end our invention comprises the following objects: first, to confine the effect of a plurality of magnetic poles upon one or more pole-pieces; second, to give the pole-pieces such conformity as will enable the windings to be placed directly upon them rather than upon the magnets proper; third, to so shape the pole-pieces as to accommodate a large number of turns of the wire and also to decrease the loss of effective magnetic lines; fourth, to increase the general efficiency of the magnets, and, fifth, to provide a more direct path for the magnetic lines of force and also to concentrate their effect within a comparatively small area.

Reference is to be had to the accompanying drawings, forming a part of this specification, in which similar characters of reference indicate corresponding parts in both figures.

Figure 1 is a perspective view of the telephone-magnet complete, the windings being removed, as indicated by dotted lines; and Fig. 2 is an inverted plan view of the complete magnet, showing how the pole-pieces are mounted upon the magnetic members and thus energized.

A pair of permanent steel magnets 3 4 of arcuate shape are surmounted by two semicircular permanent magnetic members 5 6, and over these are two other semicircular steel magnets 7 8. All of the like poles are disposed adjacent to each other, and the separate magnetic members are connected together by means of screws 9. A pair of detachable pole-pieces 10 11 are bent slightly, so that their tips 10^a 11^a are vertical when the magnetic members are horizontal, the pole-pieces 10 11 being inclined obliquely, as indicated in Fig. 1. The pole-pieces terminate

in pedestals 12 13 integral therewith, these pedestals being secured to the magnets 5, 6, 7, and 8 by means of screws 14 15, which are adapted to secure the entire construction within a suitable casing. Mounted upon the pole-pieces 10 11 are spool ends 16, 17, 18, 19, and 19, of elliptical form, made, preferably, of fiber, and mounted rigidly over the spool ends 18 19 are brass washers 20 21. Both the brass washers and the spool ends are secured rigidly upon the pole-pieces 10 11 and 65 form angles to the general direction of extension of the pole-pieces. By this arrangement the spool ends and washers are disposed in planes parallel to those of the permanent magnets, notwithstanding the obliquity of 70 the pole-pieces.

In the construction shown all of the north-seeking poles of the permanent steel magnets are disposed toward the left, according to the view shown in Fig. 2, and all of the south-seeking poles are disposed toward the right in said figure. The pole-pieces 10 11 are thus of opposite polarity, and the tips 10^a 11^a of these pole-pieces are adapted to throw off a comparatively large number of lines of force. 80 The windings are indicated by dotted lines at 22, but are removed for the sake of clearness.

It will be noted that the pole-pieces 10 11 extend from a plane passing equatorially through the permanent magnets 3 4 to a 85 point disposed a considerable distance from this plane. In other words, the length of the pole-pieces 10 11 is increased, because of the fact that these pole-pieces extend practically to the bottom of the composite ring formed 90 by the several permanent magnets. It will be noted, further, that owing to the obliquity of the pole-pieces 10 11 the length of these pole-pieces is still further increased. The result is that a comparatively large amount 95 of wire can be wound upon these pole-pieces intermediate of the spool ends 16 18 and 17 19.

This magnet is of peculiar service in connection with receivers used in wireless telegraphy and related arts, in which it is desirable to increase to the greatest extent the lines of force proceeding from the pole-pieces.

The conformity of the entire structure enables it to be readily fitted into the circulation-casing used for the so-called "watch-case-receiver."

Referring to Fig. 1, it will be noted that

each pole-piece 10 11 is acted upon magnetically by six different magnet-poles all of the same sign, so that the tendency is to confer upon each pole-piece a powerful degree of 5 magnetism.

While we show magnets having the form of semirings, we do not limit ourselves to this particular construction, for obviously various modifications may be made in the form 10 of the permanent magnets without departing from the spirit of our invention. Neither do we limit ourselves to the particular number of permanent magnets shown nor to the precise form of the pole-pieces illustrated. 15 15 As the screws 14 15, connecting the magnets together, are removable, it follows as a matter of course that any number of the permanent magnets may be removed without changing any essential feature of the invention. 20 The effect being simply one of degree. It will be further noted that by thus arranging the several magnetic semirings in juxtaposition, as above described, all spaces and gaps are completely filled and the space occupied by the magnetic members is reduced 25 to a minimum.

Having thus described our invention, we claim as new and desire to secure by Letters Patent—

30 1. In a telephone-magnet, the combination of a pair of magnetic members having the form of semirings and paired together, the positive poles being in juxtaposition, and the negative poles being also in juxtaposition,

35 a pole-piece connected with both of said positive poles, another pole-piece connected with both of said negative poles, said pole-pieces slanting toward each other, and spool ends mounted upon said pole-pieces and disposed obliquely in relation to the general direction thereof.

40 2. In a telephone-magnet, the combination of a plurality of magnetic semirings each provided with a positive pole and with a negative pole, the negative poles being immediately adjacent to each other, a pole-piece connected with both of said positive poles and extending therefrom, and spool ends mounted upon said pole-piece and disposed obliquely in relation thereto.

45 3. A telephone-magnet, comprising magnetic members and separate pole-pieces mounted thereupon, said pole-pieces being inclined obliquely in relation to said magnetic members for the purpose of giving them a comparatively long winding-space, and spool ends mounted upon said pole-pieces and inclined relatively to the general direction thereof.

50 60 4. A telephone-magnet, comprising magnetic members and pole-pieces mounted thereupon, said pole-pieces converging toward each other so as to concentrate the magnetic lines of force within a comparatively small area, and spool ends mounted upon said pole-

pieces and inclined relatively to the general length thereof.

5. A telephone-magnet, comprising a plurality of members permanently magnetized, each member being provided with a positive 70 pole and with a negative pole, the positive poles of the two members being brought together and the negative poles of said members being also brought together, a pair of pole-pieces each provided with a base, one of 75 said bases being connected rigidly with said positive poles and the other of said bases being connected rigidly with said negative poles, said pole-pieces being inclined toward each other, and having their tips extending 80 vertically when the magnetized members are horizontal and flat spool ends mounted upon said pole-pieces and disposed parallel to said members.

6. A telephone-magnet, comprising a number of magnetic semirings arranged substantially in the form of a circle, a plurality of pole-pieces acted upon inductively by said magnetic semirings and magnetized thereby, said pole-pieces being disposed upon opposite 90 sides of said circle and inclined toward each other so as to be comparatively near together at a point adjacent to the center of said circle, the said pole-pieces being bent so that their tips extend vertically when the magnetic members are horizontal, and spool ends mounted upon said pole-pieces and disposed parallel to the general plane of the 95 circle made up of said semirings.

7. A telephone-magnet comprising a pair 100 of permanent magnetic members of arcuate shape having their ends spaced apart, two pairs of semicircular magnetic members surrounding the same, means for securing the said members together, substantially in the 105 form of a circle, detachable pole-pieces having integral bases fitting in the spaces between the ends of the first-mentioned pair of magnetic members, and secured to the semi-circular magnetic members, the said pole-pieces being inclined toward each other and bent so that their tips extend vertically when the magnetic members are horizontal, and spool ends mounted upon said pole-pieces and disposed parallel to the general plane of the 110 circle made up of said magnetic members.

8. A telephone-magnet, comprising a plurality of semirings of magnetic material placed together so as to form a composite structure of annular form and provided with 120 apertures, pole-pieces provided with bases fitted into said apertures, said pole-pieces being connected with said semirings and extending toward each other, the pole-pieces being bent so that their tips extend vertically 125 when the said semirings are horizontal, spool ends mounted upon the lower part of the body of the pole-pieces adjacent to their bases, spool ends mounted upon the vertically-extending tips of said pole-pieces, 130

and metallic washers secured to the tips of said pole-pieces over said spool ends.

9. A telephone-magnet, comprising a plurality of magnetic members, pole-pieces connected therewith, and spool ends mounted upon said pole-pieces and inclined relatively to the general length thereof.

10. A telephone-magnet, comprising a plurality of magnetic members, pole-pieces connected therewith, the said pole-pieces having their main or body portions inclined toward each other and their tips extending

parallel with each other, and spool ends mounted upon the pole-pieces and disposed in planes parallel to those of the magnetic members.

In testimony whereof we have signed our names to this specification in the presence of two subscribing witnesses.
